Primary Examiner — Wendy L Arminio

(57) **CLAIM**

The ornamental design for a closure cap, as shown and described.

DESCRIPTION

1. Closure cap

1.1 : Front

1.2 : Perspective

1.3 : Back

1.4 : Right

1.5 : Left

1.6 : Top

1.7 : Bottom

The dot-dash-dot broken lines depict the boundaries of the claim. All other broken lines depict portions of the closure cap that form no part of the claimed design.

1 Claim, 7 Drawing Sheets(56)
